BUTTON ORIENTING AND ATTACHING
MACHINEFrederick H. Peterson, Watertown, Conn., assignor
to The Patent Button Company, Waterbury,
Conn., a corporation of Connecticut

Application June 8, 1940, Serial No. 339,547

1 Claim. (Cl. 218—12)

My invention relates to new and useful improvements in button-orienting and attaching machines, and more particularly to the cup or hopper and its improved raceway, and is a continuation in part of my co-pending applications referred to below.

One of the objects of the present invention is to utilize the same form of hopper as shown in certain of my pending applications, to wit, the one filed by me on December 12, 1938, for Orienting button-attaching machine, bearing Serial Number 245,278 and the one filed by me on June 23, 1939, for Orienting button-attaching machine, bearing Serial Number 280,859, and a similar form of raceway with its enlarged portion at its upper end. However, I additionally provide a spring-pressed arm or wall, which is a portion of the raceway to thus further overcome any tendency of jamming of the buttons as they pass from the hopper into the concentric raceway just previous to passing down the chute to the attaching station.

In the former applications above-mentioned and in the present application, the buttons to be oriented are provided with flats on their hubs and a step or guiding wall on the ends of the hubs, so that when the buttons pass through offset radial grooves formed in the lower wall of the hopper into the raceway, the buttons are in a certain aligned position with respect to the grooves. Then, as they free themselves from the grooves of the hopper and pass into the raceway, they are revolved by friction so that the flats on the hubs of the buttons (which bear a certain relation to the insignia on the face of the button) will be parallel with the wall of the raceway into the chute.

Due to the fact that buttons in passing into the raceway may contact with buttons which are already in the raceway and also due to the close limits of the width of the raceway with relation to the width of the hubs of the buttons as measured through the flats, there was occasionally a slight jamming of the buttons. By having an enlarged portion of the raceway above the horizontal line through the center of the hopper, these jammed buttons may be carried on up into the enlarged portion where they are freely revolved and then drop back into the hopper. There is a stop provided so that buttons which once reach this position cannot come back into the chute because they are out of their aligned position.

The present invention, however, contemplates making a portion of the outer wall of the raceway (the inner wall being the periphery of the

hopper) of a yielding nature so that any jamming tendency is still further overcome as the outer wall of the hopper may yield or be moved back slightly and let the buttons find their true aligned position.

Still another object of the invention is to have this spring-pressed arm extend practically around or along the entire distance wherein the buttons pass from the hopper into the raceway, thus providing a flexibility in the raceway that was not present in the earlier forms of machines.

With these and other objects in view, the invention consists in certain new and novel features and combination of parts, as will be hereinafter more fully explained and pointed out in the claim.

Referring now to the drawings showing a preferred embodiment,

Fig. 1 is a top plan view of the hopper and raceway of a button-orienting and attaching machine and showing a button being tumbled, a button passing through the hopper into the raceway, and a further button in its finally aligned position within the raceway;

Fig. 2 is a fragmentary side elevation of the hopper and the raceway and showing the spring-pressed arm that forms an important part of the raceway;

Fig. 3 is a fragmentary top plan view of the base plate and the raceway before the parts are assembled and mounted thereon;

Fig. 4 is a sectional view taken on the line 4—4 of Fig. 1 and showing how a button passes in a perfectly aligned position through the hopper;

Fig. 5 is a fragmentary transverse sectional view taken on the line 5—5 of Fig. 1;

Fig. 6 is a detail plan view of the spring-pressed arm;

Fig. 7 is a detail of the button chute extension which connects the raceway with the chute;

Fig. 8 is a side elevation thereof;

Fig. 9 is an end view thereof;

Fig. 10 is a bottom plan view of the type of buttons to be used in the machine;

Fig. 11 is a face view thereof; and

Fig. 12 is a side elevation of a button showing the aligning wall on the end of the hub and the flat on the inner side of the hub.

Referring to the several views and to Fig. 3 for the moment, there is fragmentarily shown a substantially circular base plate 1 with the extension plate 2, which will be secured to a bracket 3 (Figs. 1 and 2) for supporting the same.

There will also be seen the milled channel or groove 4 formed in the extension plate 2 extending up into the circular portion of the base plate, as at 5.

There may further be seen the concentric overhanging wall 6 (near the top of the plate to the right), which terminates at 7. The outer periphery of the base plate is also milled to form a cut-out portion or recess at 8, which portion extends downwardly to adjacent the upper end of the milled channel 4. It is in this recess or cut-out portion 8 that a spring-pressed arm, later to be mentioned, is to be mounted.

The bottom of the recess 8, however, extends above the surface of the base plate, as may be seen in Fig. 5, as the head of the button has to pass under the arm which is mounted in this recess.

Referring now to Figs. 1 and 2, showing the base plate and the rotating hopper or cup and other parts in position, it will be noted that the cup and its mounting on the base plate are identical with the arrangement shown in my pending application, to wit, the one filed by me on June 23, 1939, for Orienting button-attaching machine and bearing Serial Number 280,859.

Briefly, there is a stud 9 mounted in the base plate 1, which stud, in turn, is operated from a clutch 10, which clutch is driven through a gear 11 from a motor and reduction gearing (not shown). The stud is also provided with a sleeve arrangement 14, so that should a button become jammed, the sleeve on the stud may remain idle together with the cup, while the stud rotates therein and thus does not damage the driving mechanism.

As heretofore-mentioned, the driving means and mounting of the hopper do not form a part of the present invention.

However, it might be mentioned that to remove the hopper, the handle 12 may be pressed to withdraw the nose 12' of the dog from a ring or groove 13 formed in the sleeve 14 and the hopper may then be bodily moved upwardly off the stud. The hopper is rotated through the sleeve 14 by a small pin 15, which pin engages a notch 16 formed in the hub 17 of the hopper, all shown and described more clearly in my application heretofore-mentioned.

Also the under periphery of the hopper is provided with offset radial grooves 18, these grooves each having an undercut wall or step 19, as may be seen in Figs. 1, 4 and 5, so that the buttons, to be later mentioned, may only pass through the respective grooves in a certain aligned position with respect to the grooves.

Referring again to the hopper which is shown in Fig. 1 in its mounted position, there is a spider 20, which extends from the inner periphery of the hopper to the hub 17, and there are the small projections or vertical ribs 21 to cause the buttons to tumble when the hopper is revolved. As heretofore-mentioned, this follows the exact structure as outlined in the above-mentioned applications.

The base plate 1 is also provided with a well 22 with the slanting base 23, so that any buttons carried up a raceway 37, that is, along the overhanging wall 6 to the well will drop into the well and then back into the hopper to be again tumbled or rotated until they successfully pass through one of the offset radial grooves 18.

In the milled channel 4 is secured the chute 24 with its overhanging walls 25, while at the upper end of the chute may be seen the chute

extension 26 with similar overhanging walls, the forward end 27 of one wall being cut on an arc to correspond to the upstanding peripheral wall 21' of the base plate, which wall 21' practically encircles the said hopper.

An end view of the chute extension 26 is shown in Fig. 9, which really is a continuation of the chute 24. However, it is easier to mill this small extension and position it in place rather than mill the chute at this end or mill the base plate at this point.

Referring now to Figs. 1 and 6, there may be seen the arm 28 with its arcuate face 29 and its pivotal point 30. There is a slightly elongated opening or aperture 31 near the outer end of the arm and beyond this may be seen the cut-out portion 32 to carry the block 33, which is held in place by the bolt 34 and pin 35, and carries the downwardly extending coil spring 36, which is to project into the raceway 37. One wall of the raceway is defined by the arcuate surface 29 of the arm 28 while, of course, the outer periphery 38 of the hopper defines the other side of the raceway. This arm 28 pivotally fits in the heretofore-mentioned recess 8 and its arcuate surface 29 is, in reality, a part of the raceway.

The side edge of the extension plate 2 carries the spring 39, which bears against the outer edge of the arm 28, as may be seen in Figs. 1 and 2 to hold the arm in its normal position.

There is a pin 40, which passes through the elongated slot 31 in the arm 28 and is threaded within an opening 41 in the hopper plate 1, which pin 40 rests against the rear wall of the opening 31 to hold the arm in its normal spring-pressed position. It will be noticed that the arcuate face or edge 29 of the arm normally extends slightly inwardly beyond the peripheral edge of the wall 6 (Fig. 1), so that, in reality, the raceway is enlarged at a point just above the upper edge of this arm 28.

The coil spring 36 extends into the raceway just below the upper end of the arm so that when any buttons, hereinafter to be mentioned, are carried up into the enlarged portion of the raceway, they may not return to the chute except by again passing through the hopper. This is necessary because after the buttons once get into this enlarged portion, they will rotate out of their properly oriented or aligned position.

The type of button to be oriented is shown in Figs. 10, 11, and 12, and in Fig. 4 I have shown how the button passes through the offset radial grooves in the hopper. Also in Fig. 5, I have shown a button as having passed into the raceway and free to pass down the chute.

The buttons are similar to those shown in Patent Number 2,170,091, granted to me and Rollin R. Clarke on August 22, 1939, for Tack buttons, and in Patent Number 2,170,092, granted to me and Rollin R. Clarke on August 22, 1939, for Tack buttons, with the exception that the flats and the end wall are positioned at a slightly different angle to the insignia than those shown in the patents.

It might be mentioned briefly that the hub has two flats 47 and 48 with an additional step or aligning wall 49 on the end of the hub, so that the buttons may only pass through the grooves 18 when in one position and the walls 19 of the grooves cooperate with the aligning walls or steps 49 in the ends of the hubs of the buttons. The face of each button is provided with insignia 50 bearing a definite relation to the flats, and in the present instance the flats

are at an angle of 20° to the vertical axis of the insignia, as the chute extends at such an angle to a line drawn through the central axis of the hopper and the attaching station (not shown).

Also, the distance (raceway) between the arcuate face 29 of the arm 28 and the side wall 38 of the hopper is slightly less than the major diameter of the hub of the button but slightly greater than the width measured on the minor axis of the hub, that is, across the flats, which permits the button to slide only when in proper position within the raceway.

It will be understood that I have not shown or described operating and driving parts of the orienting and attaching machine, but it might be noted that the hopper is preferably continuously rotated, so that the raceway will be well supplied with buttons, which insures that on an attaching operation there will always be a button under the plunger (not shown).

It will also be understood that the hopper will be partially filled with buttons and rotated in an anti-clockwise direction. Then, when a button aligns itself in position, as shown in Fig. 4, it will pass through its offset radial groove into the raceway. However, it still is not in its finally aligned position. As the major part of the face of the button is resting on the bottom of the raceway, the continued movement of the hopper, while a portion of the button is still in the groove, will tend to revolve the same by friction in a clockwise direction, at the same time, of course, slightly elevating the button in the raceway. When the flats 47 and 48 become parallel with the periphery 38 of the hopper and the side face 29 of the arm, the buttons are then free to pass down the raceway into the chute. Should there be a tendency for any button to jam during this elevating movement or striking of the buttons in the raceway, the arm 28 may yield slightly until such time as the button aligns itself correctly, that is, with the flats parallel, after which the arm will then be pressed back by the spring action to its normal position.

Any buttons which are carried beyond the coil 45 spring 36 are free to rotate in the enlarged por-

tion of the raceway and will be carried up into the well 22 and again drop back into the hopper. However, by providing the coil spring 36, as heretofore shown, any buttons once carried into the upper portion of the raceway will never fall back thereinto.

Thus, by providing the spring-pressed arm and locating it opposite the place where the buttons enter the raceway, any jamming of the buttons will be provided for, that is, the arm may move back slightly to, in reality, slightly enlarge the width of the raceway, but the arm being under spring pressure will never let the buttons revolve from their desired oriented position.

Many slight changes are possible in the construction hereinbefore set forth without in any way departing from the spirit and scope of the invention.

Having thus described my invention, what I claim as new and desire to secure by Letters Patent is:

In a button-orienting and attaching machine, a rotatable hopper having offset radial grooves through which are adapted to pass buttons in a certain aligned position with respect to said radial grooves, a concentric wall spaced from the periphery of the hopper to form a raceway for receiving the buttons, a chute registering with the lower end of said raceway, a portion of the said concentric wall being recessed and a spring-pressed arm being an arc of the concentric wall and being pivotally mounted in the recessed portion forming a part of the raceway, said spring-pressed arm being pivoted below a horizontal line drawn through the central axis of the hopper and said spring-pressed arm yieldably preventing the buttons from jamming when in said raceway while still retaining them in an oriented position, the upper portion of said raceway being enlarged to receive buttons carried up to said portion, and a stop located at the lower end of the enlarged portion to prevent any buttons from returning to said raceway after once having been carried to the enlarged portion.

FREDERICK H. PETERSON.
